EXTENSIBLE AERIAL DELIVERY CONTAINER

Frank G. Manson and James J. Maskey,
Dayton, Ohio

Application October 16, 1941, Serial No. 415,264

6 Claims. (CL 244—137)

(Granted under the act of March 3, 1883, as
amended April 30, 1928; 370 O. G. 757)

The invention described herein may be manufactured and used by or for Government for governmental purposes, without the payment to us of any royalty thereon.

This invention relates to parachute apparatus, and particularly to improvements in parachute-carried containers for safely delivering articles or supplies from aircraft to the earth.

An object of the invention is to provide a device of this kind which is particularly applicable for delivering supplies which are put up in cartons of different sizes.

Another object of the invention is to so construct the device that a considerable range of combinations of sizes of cartons may be delivered in a single container.

Another object is to so construct and arrange the device that it may be opened after delivery and the contents removed in as little time and with as little labor as is possible.

Another object is to provide apparatus of this character which will be of light weight and low cost, yet of sufficient strength to deliver the articles or supplies safely.

Another object is to so associate the parachute pack and the container for the articles as to insure positive and safe operation at all times.

Other objects and advantages will be apparent as the invention is described in detail and reference is made to the drawings wherein:

Fig. 1 is a perspective view of the assembled device.

Fig. 2 is a rear end view of the complete device.

Fig. 3 is a broken-away perspective view showing part of the interior construction and the contents.

Fig. 4 is a front end view of the cover portion of the container before the reinforcing members have been added, and without the parachute pack.

Fig. 5 is a view similar to Fig. 4 showing how the cross section of the container may be arranged for carrying a combination of cartons which have greater height than width.

Fig. 6 is a view similar to Fig. 5 except that it is arranged to carry cartons of substantially square cross section.

Fig. 7 is a fragmentary view taken at 7—7 of Fig. 5, showing how surplus end area is taken up in adjusting the cover for different shaped cartons.

Like numerals refer to like parts throughout the several views.

In the drawings, the outer or cover portion 10

is made in the shape of a hollow prism, with the rear end 12 open, and with the front end closed by a panel 14. Front end panel 14 is notched out as at 16, 18, 20, and 22 at the corners (see Fig. 4). The side panels 24 and 26 and the top panel 28 and bottom panel 30 are permanently joined together and to the end panel 14. Cover portion 10 is preferably constructed of fabric such as cotton duck or the like.

Rows of ties 32 are spaced along the edges where the side panels 24 and 26 join the end panel 14, and parallel rows of ties 34 are stitched to the end panel 14 as far back from the ties 32 as the depth of the notches 16, 18, 20, 22.

Rows of ties 36 are spaced along the edges where the top panel 28 and bottom panel 30 join the end panel 14, and parallel rows of ties 38 are stitched to the end panel 14 as far back from the ties 36 as the depth of the notches 16, 18, 20, 22.

When the carton, or cartons, which are to be carried have greater height than width, the side ties 32, 34, Fig. 4, are tied up close in pairs as at 40, Fig. 5, while the top and bottom ties 36, 38 are tied loosely or left open as at 42. Fig. 3 shows cartons 33 and 35 stacked higher than wide.

When the carton or cartons which are to be carried are of equal width and height, the top and bottom ties 36, 38, Fig. 4, are tied close up in pairs as at 44, Fig. 6, while the side ties 32, 34 are tied loosely or left open as at 46.

When either set of ties is tied up close, a fold is necessarily made in the surplus portion of the end panel 14, such fold appearing as at 48, Fig. 7. Figs. 5 and 6 show the extremes of dimension alteration which may be made in the end panel 14, but it will be readily conceivable that any intermediate ratio of length to width may be had in the end panel by modifying the extent of the folds 48 with the ties.

The side panels 24, 26 and the top panel 28 and bottom panel 30 of the cover 10 are made somewhat longer than the cartons which are to be carried, so that the extra length may be brought together by a drawstring 50 to form a closure around the back end, the drawstring being tied with a single tie 52.

Lengths of reinforcing webbing 54 extend horizontally along the side panels 24 and 26 and slightly around the front and back ends 14 and 12, the strips being stitched to the sides except at intervals 56 where they are left loose to form loops for the passage of the adjusting straps 58.

Straps 56 pass completely around the cover and are provided with adjusting buckles 58.

The bottom panel 30 of the cover portion 10 is also reinforced by stitching an additional fabric layer thereto with a stiffening plank 60 therebetween. A carrying frame 62 is formed of steel rod and lies lengthwise under the top panel 28 of the cover. Bridges 64 are welded to frame 62 and arch upwardly through slots 66 in the cover, which are reinforced by pads 68. The bridges 64 are properly spaced to engage the hooks of the bomb rack of the carrying plane.

Around the closed ends 70 of the frame 62 short strips 72 are stitched, these strips carrying stirrups 74 into which the spring snaps 76 are snapped. The top 28 has slots 80 through which the strips 72 emerge, the slots being reinforced by pads 82.

The parachute pack 84 is fastened to the front end 14 by pairs of ties 40 which are passed through suitable loops on the back of the pack casing 86. The casing 86 may be made of duck or similar material with reinforcing webbing 88 and with a stiffening member in the bottom, the bottom being that side of the pack casing which is held against the front panel 14 of the cover portion 10 by the ties 40.

The casing 86 is of the purse type, being provided with a single split at 90 with grommets 92 along the edge, through which a light lacing 94 passes to hold the two sides together. The canopy 96 may be made of plain cotton fabric design with narrow webbing for shroud lines which are divided into two groups and joined to the risers 78. The risers 78 enter the pack casing at 88.

The static line 100 extends first to the bottom of the pack, then back up over the lacing to the opening 98 where it enters the casing and is attached by a break cord to the top of the canopy 96. Line 100 is tacked at several places to the lacing 94 as at 102. The upper end of the static line has a spring snap 104 for attachment to a suitably positioned ring on the plane.

Having described our invention, we claim:

Having described the combination, in a container for aerial delivery of cartons of varying sizes, a fabric cover in the form of a hollow prism with the back end open, a drawstring around said open end for closing said end around the end of the cartons, the front panel having parallel rows of ties extending lengthwise and crosswise of said panel, whereby folds may be tied in said panel to change the length or the width or both, the bottom panel of said cover being in two stitched-together layers with a stiffening plank between said layers, a rectangular metal frame lying between the top of the cartons and the top panel of the cover, parachute riser strips attached to the ends of the frame and extending upwardly through reinforced openings in said top panel, riser attaching stirrups in the ends of said strips, bomb rack bridges intermediate the strips joining opposite sides of the frame and extending through reinforced openings in the top panel, spaced-apart lengths of reinforcing webbing stitched horizontally to the side panels of the cover member leaving spaced-apart unstitched portions for adjusting strap loops, adjusting straps having buckles passing through said loops and around the cover, a

parachute pack containing a canopy, said pack being fastened to the front panel, a static line extending from the top of the canopy within the pack, and risers extending from the bottom of the canopy to the said stirrups.

5 the canopy to the said support.

2. The combination, in a container for aerial delivery of cartons of varying sizes, a flexible cover in the form of a box with one end open, a drawstring around said open end for closing said end around the ends of said cartons, the front panel having parallel rows of means extending both lengthwise and crosswise of said panel for holding folds in said panel thereby to change its length or width or both, the bottom panel of said cover being in two layers with a stiffening member between the layers, a frame lying between the top of the cartons and the top panel of the cover, means for attaching parachute risers extending upwardly from the ends of the frame through openings in said top panel, means on said frame for attachment to a bomb rack extending through other openings in said top panel, reinforcing strips stitched horizontally to the side panels leaving unstitched parts for adjusting strap loops, 10 adjusting straps in said loops encircling the cover, a parachute pack attached to the front panel, and risers extending from said pack to said riser attaching means.

15

20

25

attaching means.

3. The combination, in an aerial delivery container, of a flexible cover in the form of a box with the front end closed, the panel forming the closed end having means to hold folds therein to alter the size of said panel, the bottom panel of said cover having a stiffening member secured thereto, a frame on the underside of the top panel, means extending upwardly from said frame through said top panel for attaching parachute risers, means extending upwardly from said frame through said top panel for attachment to bomb racks, buckle straps closely surrounding said cover, a parachute pack on the front panel, and risers extending from said pack to said riser attaching means.

4. In an extensible aerial delivery container, a
flexible cover in the shape of a box with the front
end closed, the panel forming the closed end having
means to hold folds therein to alter the size
of said panel, a frame associated with the top
panel having means for attachment to parachute
risers and means for attachment to a bomb rack,
and adjustable buckle straps surrounding said
cover and frame.

5. In an extensible delivery container, a flexible cover member in the form of a hollow rectangular prism with one end closed, the rectangle comprising the closed end being cut away at the corners, and parallel rows of ties proximate the four edges of the rectangle, for holding folds in said rectangle alongside said edges whereby either of the dimensions of said rectangle may be decreased.

6. In an extensible container, a flexible cover in the form of a hollow prism with one end closed, the panel forming the closed end being notched out at the corners, and means to hold folds in said panel either lengthwise or crosswise to change the normal dimensions of said panel.

FRANK G. MANSON.
JAMES J. MASKEY.
